DEVICE FOR SUPPORTING, DRIVING, AND PRESENTING VIEWS, IMAGES, ADVERTISEMENTS, AND EVEN ARTICLES

André George, Paris, France

Application December 14, 1932, Serial No. 647,231
In Luxembourg December 19, 1931

2 Claims. (Cl. 40—98)

This invention relates to devices for supporting, driving and presenting views, images, advertisements and even articles, and more particularly concerns projection or presentation apparatus the supports of which, usually in the shape of plates or frames receiving the images or advertisements to be projected or presented, are mounted on suitable bands.

The projection or presentation apparatus in question devised up to now were usually somewhat cumbersome, and this particularly owing to the cumbersomeness of the bands carrying the plates or frames and of the systems driving and presenting the said plates or frames, which systems were moreover complicated and, consequently, of a relatively high cost price.

The invention has for object to provide apparatus of the type in question which are compact, very simple, and of a low cost price comparatively to existing apparatus, owing to the fact that the supporting, driving and presentation devices they comprise are themselves according to the invention of reduced cumbersomeness and very simple.

The invention is characterized by the fact that in each apparatus of the type in question, on the one hand, the band supporting the image-carrying or advertisement-carrying elements is constituted by a kind of chain having jointed links, the support itself for the element being suitably secured on each link in such a manner that the plate or surface carrying the image (or the advertisement or view) is contained in the plane best suited for the projection or presentation, that is to say in the majority of cases at right angles to the plane of the pivot spindles of the said link and parallel to the said pivot spindles; on the other hand, the device for driving and presenting the supports for the image-carrying or advertisement-carrying elements, partly constituted in the known manner by a Maltese cross and a plate driving the said Maltese cross, comprises a shaft having a square cross section actuated by the latter; this shaft directly drives the band carrying the supports for the image-carrying or advertisement-carrying elements, the links of this band exactly corresponding to the faces of the said shaft and successively fitting against one of the said faces, the element carried by one of the links being then contained in the plane best suited for the projection or presentation, that is to say in the majority of cases at right angles to the faces of the shaft against which this link fits.

As the band carrying the supports for the elements is in contact with three of the faces of the

shaft driven by the Maltese cross, it is obvious that at every instant the element supports carried by the links of the band are perpendicular two by two and that the support of the median element is thus at right angles to the plane of the two other elements and is perfectly clear of the same.

The invention will be clearly understood from the following complement of description and from the accompanying drawing, which complement of description and drawing are given by way of example only.

Fig. 1 is a diagrammatic end view, with parts broken away, of the device for driving the band on which are mounted the plates carrying the images of an apparatus for projecting advertisements and carried out according to the invention.

Fig. 2 is a diagrammatic plan view of the said driving device.

Fig. 3 is a diagrammatic end view (seen from the side opposite to that shown in Fig. 1) of the said driving device with the band on which are mounted the plates, this driving device and the said band being constructed according to the invention.

Fig. 4 is a diagrammatic section of a link and of the element support it carries, this link forming a part of a band of a projection apparatus, the said band being devised according to a second form of carrying out the invention.

Fig. 5 is a front elevation of a link and of the element support carried by the same; the pivot spindle is shown as being removed.

In providing for instance an advertising apparatus projecting images and advertisements, and comprising a succession of plates carrying the images and advertisements to be projected, the said apparatus is constructed in the usual manner as far as the frame and projection apparatus proper are concerned, but, concerning the devices, according to the invention, for supporting, driving and presenting the plates, it is constructed in the following manner or in an approximately similar manner:

The band carrying the plates 1 is an endless band composed of links 2 assembled and joined together by means of pivot spindles. To each link 2 is secured, by any suitable means, a plate support constituted by two slides 4 in which is fitted the plate to be carried by the link along two of its edges, the said plate being held, once in position, by two bent parts 5 and 6. The plate support of each link is secured on the link, so that the plate carried by the support is perpen-

dicular to the link and parallel to the two axes of the latter.

The said band carrying the plates is supported and driven by a shaft 7 having a square cross section.

A kind of Maltese cross 8 is mounted on the shaft 7 so as to rotate with the same, this Maltese cross being alternately driven by a plate 9 carrying a claw 10, to which plate 9 is secured an abutting segment 11, in the usual manner.

The said Maltese cross 8 is rigidly secured on the shaft 7 in such a manner that when this Maltese cross 8 is at rest, the plate 9 still rotating in a continuous manner, the shaft 7 having a square cross section has one of its faces horizontal.

The plate 9 is actuated by a suitable motor, in the known manner, and through suitable transmissions.

From the foregoing and from the accompanying drawing (Fig. 3), it will easily be understood that a projection apparatus provided with the devices for supporting, driving and presenting plates carrying images or advertisements and constructed according to the invention, is of very reduced cumbersomeness and very simple. In fact, the plates carried by the endless band are so to speak piled up according to two vertical stacks, the distance separating them being function of the side of the square supporting and driving shaft and, consequently, is relatively small, and a chain of small length can carry a large number of plates. Moreover, owing to the fact that the shaft 7 has a square cross section, and is rigid, as indicated, with the Maltese cross 8, at the same time as it supports and drives the band carrying the plates, it ensures the presentation of each of the plates successively and their correct positioning for projection, without the help of any other device.

The intermittent periods of rest of the Maltese cross 8 determine the periods of presentation of the plates.

The pivot spindles for the links can be conveniently constructed so as to be easily removed and replaced in position, for instance by forming these spindles in such a manner that one of their journals (journal 12) is longer than the other and that these spindles, or at least their shorter journal, are so mounted as to have sufficient play in their bearings to be easily removed, a suitable spring 13 being used for holding them in position. It is then very easy to do away with a number of links, or, on the contrary, to add a

number of links, and to thus readily vary the number of projected views, images, or advertisements. As the number of supports can exactly correspond to the number of elements, there is therefore no interruption (blanks) in the presentation of the elements (views, projection, etc.).

The links of the chains carrying the supports for the elements and the said supports can also be conveniently constructed in such a manner as to form a single unit which can be easily manufactured by cutting out and bending operations, as shown in Fig. 4 of the drawing. The plate 1 carried by each support is then held in position by a bent portion 14 and two small suitable springs 15 which constantly press the plate 15 against the support, the slides being omitted.

It will be understood that the invention is not limited in any way to the mode of application and to the forms of construction which have been more particularly indicated, as it includes on the contrary all modifications of the same.

What I claim as my invention and desire to secure by Letters Patent is:—

1. A device of the character described including a rotatable shaft the main portion of which is square in cross section, a Maltese cross fixed directly to the squared portion of the shaft, means cooperating with the Maltese cross for effecting intermittent rotation of said shaft, the squared portion of the shaft and the Maltese cross being so fixed relatively to each other that during each of the intermittent stoppages the upper face of the squared portion of the shaft is in a horizontal position, a chain operating about the squared portion of the shaft, plate supports carried by said chain, and said chain including a plurality of links each of which carries a plate support and has a length substantially corresponding to the width of the squared portion of said shaft so that when each link reaches the top it is supported on the upper face of the squared portion of the shaft and maintains the plate support perpendicular to said upper face.

2. In a device of the character described, an endless band in the form of a chain composed of a plurality of plate supporting links and pintles connecting the links together, each pintle having a short journalling portion and an elongated journalling portion, and a coil spring arranged about the elongated journalling portion for yieldingly and releasably holding the short journalling portion into position.

ANDRÉ GEORGE.
